CLAIM

The ornamental design for wall-mount rifle rack, as shown and described.

DESCRIPTION

FIG. 1 is a perspective view of wall-mount rifle rack showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken line portions of the drawing figures are included to show portions of the article that are not part of the claimed design.

1 Claim, 7 Drawing Sheets
